UNITED STATES PATENT OFFICE.

JAMES HARMER KNIGHT, OF WESTTOWN, PENNSYLVANIA.

LOOSE-LEAF BINDER.

1,372,960.

Specification of Letters Patent. Patented Mar. 29, 1921.

Application filed November 21, 1919. Serial No. 339,572.

To all whom it may concern:

Be it known that I, JAMES HARMER KNIGHT, a citizen of the United States, residing at Westtown, in the county of Chester 5 and State of Pennsylvania, have invented certain new and useful Improvements in Loose-Leaf Binders, of which the following is a specification.

One object of my invention is to provide 10 a loose leaf binder of an extremely simple and durable construction which will securely bind together a number of sheets of paper, cardboard or the like in book form and which will be easily operative to permit the 15 insertion of additional leaves or the removal of leaves therefrom.

Another object is to so construct my improved loose leaf binder that by a simple 20 manual movement it can be readily detached or placed in binding position.

A further object is to so design my invention that it can be quickly and easily made.

These objects, and other advantageous 25 ends which will be described hereinafter, I attain in the following manner, reference being had to the accompanying drawings in which—

Figure 1 is a fragmentary top plan view showing my invention in the position which 30 it occupies when binding a number of sheets of paper or the like,

Fig. 2 is a sectional elevation taken on the line 2—2 of Fig. 1,

Figs. 3 to 6 inclusive are diagrammatic 35 views, partly in section, showing the steps of movement required to attach the parts of my improved binder,

Fig. 7 is a top plan view of a flexible securing strip which forms a part of my invention,

Fig. 8 is a front edge view of the securing strip of Fig. 7,

Fig. 9 is a fragmentary section taken on the line 9—9 of Fig. 2,

Fig. 10 is a view of similar nature to Fig. 1 showing a slight modification in the form of my invention,

Fig. 11 is a sectional elevation taken on the line 11—11 of Fig. 10, and

Fig. 12 is a diagrammatic view showing the flexible securing strip of Figs. 10 and 11 in a position illustrating the function of limiting hoods during one step of the operation of attaching the flexible securing strip.

Referring to Figs. 1 to 9 inclusive, 16 represents a book cover which may be of any

usual construction having a movable hinged top section 17 and a bottom section 18. The cover 16 is preferably made, intermediate the top and bottom sections, of flexible material, such as cloth and has an upper folded portion 19 and a lower folded portion 20. The lower folded portion 20 embraces a base plate 21 which has three posts 22, 23 and 24. These posts are arranged in a row longitudinally of the base plate 21 and the post 23 is positioned between the posts 22 and 24 and is spaced from said latter posts as clearly shown in Figs. 1 and 2.

The folded portion may be stitched as 70 shown at 25 to retain the base plate 21 in position and the posts 22, 23 and 24 project upwardly through the upper part 26 of the folded portion 20 to prevent lateral movement between said folded portion and the 75 base plate 21. Any number of sheets 27 of paper, cardboard or the like which are to be bound can be placed upon the posts 22, 23 and 24; said sheets being provided with holes to permit the posts to penetrate them. 80 The posts also pass through the folded portion 19 and a clip 28 is attached to the folded portion 19 and provides a guideway for a flexible securing strip 29. This securing strip 29, as shown in detail in Figs. 7 85 and 8, is preferably made of spring steel and normally bowed upwardly at its ends, as shown in Figs. 3 and 8. The strip 29 is provided adjacent its ends with two holes 30 and 31 adapted to normally register with 90 the posts 22 and 24, as shown in Fig. 3. The strip 29 is also provided with another hole 32 and this hole 32, when the holes 30 and 31 are in register with the respective posts 22 and 24, is out of register with the 95 intermediate post 23, as clearly shown in Fig. 3.

The posts 22 and 24 are provided with notches 33 and 34 respectively; said notches being of a height at their outermost portions 100 which is slightly greater than the thickness of the securing strip 29. These notches 33 and 34 taper inwardly from the right hand sides of the respective posts 22 and 24 and it will be noted that the hole 32, as shown 105 in the position in Fig. 3, is located with its center to the right of the center of the post 23.

It will be noted that the clip 28 permits of a free sliding movement of the securing 110 strip 29 therethrough and merely serves to prevent the securing strip 29 from becom-

ing entirely detached from the cover. I might further state that my invention is applicable for binding a number of sheets together without any cover such as 16. For example even though the cover 16 is omitted the functioning of the securing strip 29, posts 22, 23 and 24 and base plate 21 will be the same.

Considering that a number of sheets 17 have been placed upon the posts 22, 23 and 24, the securing strip 29 is first moved into the position illustrated in Fig. 3 with the holes 30 and 31 respectively registering with the posts 22 and 24. The intermediate portion 15 of the securing strip 29 is moved into engagement with the top of the intermediate post 23 and the opposite ends of the securing strip 29 are moved downwardly by the fingers into the position shown in Fig. 4 so 20 that the upper parts of the posts 22 and 24 pass through the holes 30 and 31. The securing strip 29 is then moved longitudinally toward the left and during this action parts of the securing strip to the right of the holes 25 30. and 31 will move into the respective notches 33 and 34 as shown in Fig. 5. This movement of the securing strip 29 causes the hole 32 to move into register with the intermediate post 23 and when the ends of the 30 securing strip 29 are manually released as shown in Fig. 6, the resiliency of the securing strip 29 will cause it to move into its normally bowed position and since parts of the plate are held within the notches 33 35 and 34, the intermediate portion of the securing strip will automatically move downwardly so that the intermediate post 23 will penetrate the hole 32. Furthermore, owing to the normally bowed shape of the securing 40 strip, the part adjacent the hole 32 will tend to move downwardly into a plane below the plane including the notches 33 and 34 and will thus firmly bind the sheets 27 together and in addition will prevent any rattling 45 or accidental movement of the parts of the securing strip within the notches 33 and 34. The above mentioned movements can be done very quickly. It is merely necessary to move the end portions of the securing strip 50 downwardly and then longitudinally after which the central portion of the securing strip will snap in position over the intermediate post 23.

In Figs. 10 to 12 inclusive, I have illustrated practically the same construction as above described in detail with the exception that I have illustrated hoods 35 and 36 which are struck up or in other words pressed upwardly and formed out of the 60 same metal which constitutes the body portion of the securing strip 29. These hoods, during the initial movement of the ends of the strip, form a stop against the tops of the posts 22 and 24 so as to limit the downward 65 movement of the end portions to prevent the

securing plate adjacent its ends from being pushed downward below an alining position with the notches 33 and 34. This construction is of particular advantage when there are comparatively few sheets between the 70 binder and facilitates the attachment. In addition I have illustrated an intermediate plate 37 which has depending sleeves 38 attached thereto which penetrate the holes of the sheets of paper and also form guides or 75 bushings for the posts 22, 23 and 24. The sleeves permit the removal of a number of the sheets and hold them in proper alinement so that they can be placed back in position if it is desired to remove a sheet or 80 number of sheets which are located between the top and the bottom of the pack of sheets. Fig. 12 shows how the hoods 35 and 36 function as above described. Also in Figs. 10 to 12 inclusive I have shown the ends 29^a of the 85 securing strip bent downwardly so as to form a comfortable grip for depressing the end portions of the strip as above described.

While I have described my invention as taking a particular form, it will be understood that the various parts of my invention may be changed without departing from the spirit thereof, and hence I do not limit myself to the precise construction set forth, but consider that I am at liberty to 95 make such changes and alterations as fairly come within the scope of the appended claims.

Having thus described my invention, what I claim as new and desire to secure 100 by Letters Patent is:—

1. A binder of the character described including a base plate having notched posts and another post positioned between said notched posts; and a securing strip having 105 holes adapted to normally register with said notched posts and another hole normally out of register with said second mentioned post, said strip being depressible to cause said notched posts to initially penetrate 110 said first holes and to bring portions of said plate adjacent said first holes into alinement with the notches of said notched posts, said strip when movable longitudinally causing said portions to enter the notches 115 of said first posts and the other hole to register with said second mentioned post whereby the latter will penetrate said strip: substantially as described.

2. A binder of the character described including a base plate having notched posts and another post positioned between said notched posts; and a securing strip having 120 holes adapted to normally register with said notched posts and another hole normally out of register with said second mentioned post, said strip being depressible to cause said notched posts to initially penetrate said first 125 holes and to bring portions of said plate adjacent said first holes into alinement

with the notches of said notched posts, said strip when movable longitudinally causing said portions to enter the notches of said first posts and the other hole to register with 5 said second mentioned post whereby the latter will penetrate said strip, said securing strip being bowed inwardly from the portions including said first holes to the portion including said second mentioned hole; 10 substantially as described.

3. A binder of the character described including a base plate having notched posts and another post positioned between said notched posts; and a securing strip having 15 holes adapted to normally register with said notched posts and another hole normally out of register with said second mentioned post, said strip being depressible to cause said notched posts to initially penetrate said first 20 holes and to bring portions of said plate adjacent said first holes into alinement with the notches of said notched posts, said strip when movable longitudinally causing said portions to enter the notches of said first 25 posts and the other hole to register with said second mentioned post whereby the latter will penetrate said strip, the notches of said notched posts tapering inwardly.

4. A binder of the character described including a base plate having notched posts and another post positioned between said notched posts; a securing strip having holes adapted to normally register with said notched posts and another hole normally out of register with said second mentioned post, 30 said strip being depressible to cause said notched posts to initially penetrate said first holes and to bring portions of said plate adjacent said first holes into alinement with the notches of said notched posts, said strip 35 when movable longitudinally causing said portions to enter the notches of said first posts and the other hole to register with said second mentioned post whereby the latter will penetrate said strip; and hoods extending over said first mentioned holes and adapted to limit the amount of penetration of said notched posts through said securing strip; substantially as described.

In testimony whereof I have signed my 50 name to this specification in the presence of two subscribing witnesses.

JAMES HARMER KNIGHT.
